UNITED STATES PATENT OFFICE.

OTTO ZSCHAEMISCH, OF CORNWELLS, PENNSYLVANIA, ASSIGNOR TO VIGILANT MILLS, OF FRANKFORT, PENNSYLVANIA, A CORPORATION OF PENNSYLVANIA.

DESIGN FOR FABRIC.

40,254.

Specification for Design.

Patented Sept. 7, 1909.

Application filed July 17, 1909. Serial No. 508,250. Term of patent 3½ years.

To all whom it may concern:

Be it known that I, Otto Zschaemisch, a subject of the German Emperor, and resident of Cornwells, Bucks county, State of Pennsylvania, have invented a new, original, and ornamental Design for Fabric, of which the following is a specification.

Reference is to be had to the drawing, in which I have illustrated a piece of fabric showing my new design.

I claim:

The ornamental design for fabric as shown.
OTTO ZSCHAEMISCH.
